Inventor:

Alexander J. La Pierre,

By his Attorney, Geo. J. McMath

Patented Feb. 8, 1927.

1,617,061

UNITED STATES PATENT OFFICE.

ALEXANDER J. LA PIERRE, OF NEW YORK, N. Y.

BATHER'S SAFETY APPLIANCE.

Application filed May 29, 1926. Serial No. 112,420.

The object of my invention is to afford simple but effective buoyant means for the protection of bathers, swimmers, and those otherwise liable to immersion in water, suitable provision being made for adapting and fitting my safety appliance to the varying individual requirements of the users,—and the invention consisting in the specific construction, combination and arrangement of component parts described whereby these and other advantageous results are attained, all as hereinafter fully set forth.

In the accompanying drawings I illustrate a practical embodiment of the essential features of my invention in a body appliance of the character stated, although I do not limit myself to the identical form and construction of parts and appurtenances shown by way of exemplification, since changes may be made in minor details, and equivalent mechanical expedients resorted to, with like results, and without departing from the spirit and intent of my invention in this respect.

With this understanding:

Fig. 1, represents a perspective view of my safety appliance as connected up on attachment around the body of a wearer;

Fig. 2, is a central vertical sectional elevation thereof; and

Fig. 3, a sectional detail of one of the float air locks.

The overlapping ends of the waist belt B, are adjustably connected by a buckle b, or equivalent copulative means whereby the belt may be adapted to the girth of the wearer; and the medial front portion of said belt B, is widened to form an abdominal shield b', which also functions as a support for a series of snap studs b'', for engagement with a snap socket s, on the extension strap s', constituting the lower extremity of the bifurcated front portion s'', of the suspender brace S, the rear ends of the shoulder straps s³, s³, of which are formed with loops s⁴, s⁴, embracing the rear bight b'', of the waist belt B, or being otherwise permanently attached thereto, as may be found most expedient. The extension strap s', is connected with the lower front portion s'', of the suspender brace S, by means of an adjustive device, as for instance the buckle s⁵, shown in Figs. 1 and 2, of the drawings, for the purpose of adapting the mean length of the suspender S, as related to the belt B, the temporary attachment between the belt B,

and the suspender S, being effected by means of the snap fastenings s, and b''.

C, is a chest strap, the rear bight c, of which is slidably connected with the rear extensions of the suspender brace S, by means of loops s⁶, s⁶, as indicated more particularly in Fig. 2, of the drawings,—this connection between the said rear parts being provided for the purpose of supporting the chest strap C, in proper relation to the arm pits of the wearer. Provision is also made for detachably connecting the chest strap C, with the front portion s², of the suspender brace S, by a plurality of snap sockets s', thereon for engagement with a snap stud c', on the chest strap, or by equivalent adjustive means. The length of the chest strap C, is regulated at the overlapping ends thereof by a buckle c'', as shown more particularly in Fig. 1, of the drawings.

It will thus be seen that ample provision is made for fitting the belt B, suspender S, and chest strap C, to the torso of the wearer. The body harness equipment thus attained is designed specifically and primarily for the mounting and support of the twin wing-floats F, F, which are permanently affixed to the back members s^x, s^x, of the suspender brace S. These twin floats F, F, of my bather's safety appliance, considered in a unitary sense, are of elongate ovoidal shape, and may be made of aluminum or other suitable metal or material, or of rubber, or waterproof fabric adapted for inflation by air or gas, in which latter event, the ends of the floats F, are provided with air locks A, such for instance as that shown in Fig. 3, of the drawings, in which the tube a is formed with an internal valve seat a', for engagement with a gasket e, on the inner end of a stem extension e', of the screw closure cap E, another gasket e'', being interposed between said cap E, and the end of the tube a, to insure a positive duplex seal, thereby obviating all possibility of leakage.

It is to be noted that the twin wing floats F, F, are approximately parallel as related to each other, and their attachment longitudinally to the rear members s^x, s^x, of the suspender brace S, affords them freedom of lateral play or movement independent of the person and without inconvenience or discomfort to the wearer. Furthermore, this longitudinal extension and attachment of floats is most effective in affording proper and adequate body support, substantially

parallel with and on each side of the main portion of the spine of the wearer.

What I claim as my invention and desire to secure by Letters Patent, is:—

- 5 As an improved article of manufacture, a safety appliance of the character designated, comprising an adjustable waist belt formed with an abdominal shield, a bifurcated suspender brace the front member of which is
10 connected with said abdominal shield by ad-

justive means and the rear members of which are loop-connected with the belt, an adjustable chest strap loose-connected with the rear members of said suspender brace and adjustable on the front member thereof, and wing floats attached to the rear members of said suspender brace between the belt and the chest strap, substantially in the manner and for the purpose set forth.

ALEXANDER J. LA PIERRE.
